R. KELSEY,
PENHOLDER SUPPORT,
APPLICATION FILED NOV. 25, 1919.

Patented Apr. 13, 1920.

INVENTOR:
Richard Kelsey
by his attorney,
Charles D. Goudy.

UNITED STATES PATENT OFFICE.

RICHARD KELSEY, OF LYNN, MASSACHUSETTS.

PENHOLDER-SUPPORT.

1,336,964.

Specification of Letters Patent. Patented Apr. 13, 1920.

Application filed November 25, 1919. Serial No. 349,568.

To all whom it may concern:

Be it known that I, RICHARD KELSEY, a citizen of the United States, residing at Lynn, in the county of Essex and State of 5 Massachusetts, have invented new and useful Improvements in Penholder-Supports, of which the following is a specification.

This invention relates to a device for supporting a pen-holder in correct position for 10 writing and is particularly adapted to be used in schools where writing is being taught for the purpose of teaching pupils to hold the pen-holder and pen in correct position while writing.

15 The object of the invention is to provide a cheap, simple and durable device of the character set forth which can be readily attached to or detached from a pen-holder or pencil and which can be adjusted longitudinally of the pen-holder, so as to position said pen-holder at different angles relative to the surface which is being written upon.

20 To these ends the invention consists in 25 a pen-holder support of the character set forth in the following specification and particularly pointed out in the claims thereof.

Referring to the drawings:

Figure 1 is a side elevation of my improved pen-holder support illustrating the 30 same attached to a pen-holder positioned for writing, a hand being shown in dotted lines in connection with the pen-holder and support.

35 Fig. 2 is a side elevation of the same holder attached to a pencil and reversed in position as compared with the position shown in Fig. 1.

40 Like numerals refer to like parts throughout the several views of the drawings.

In the drawings, referring to Fig. 1, 5 is the pen-holder support and 6 is the pen-holder. The pen-holder support 5 is formed of a piece of wire, preferably spring wire, 45 with a loop 7 intermediate its ends and through which the pen-holder 6 projects, when said support is attached thereto; said support terminates at one end in an arm 8 which extends laterally across the upper 50 side of the pen-holder when in position. The other end of said holder terminates in a coil 9, constituting a foot and adapted to rest upon the surface being written upon when the pen-holder is in writing position. 55 The coil 9 is adapted to receive the little finger of the hand of the writer; a substan-

tially straight portion 10 connects the coil 9 to the loop 7 and said loop and coil are located on one and the same side of said straight portion 10.

In Fig. 2 the support is shown attached to a pencil 11 but reversed in position as compared with the position in which said support is shown in Fig. 1. The operation and function, however, of the support is 60 the same in both cases and the little finger of the hand of the writer projects through the coil 9 in each case but whereas when the support is positioned as illustrated in Fig. 1, the middle and third fingers of the 65 hand are located on the same side of the straight portion 10 as the coil 9 and loop 7. When the device is positioned as in Fig. 2, the little finger extends through the coil 9 while the middle finger is in front of the 70 portion 10 or on the opposite side of the portion 10 from the coil 9 and loop 7 and the third finger is positioned on the same side of the portion 10 as the coil 9 and loop 7. One of the principal advantages of having the device reversible is that it cannot be placed upon a pen-holder or pencil in a 75 wrong position.

In using the device, it is first attached to the pen-holder by slipping the pen-holder 80 through the loop 7 and then pressing upwardly on the arm 8 and then sidewardly until said arm extends over the upper side of the pen-holder. The wire being preferably a spring wire, the straight portion connecting the arm 8 with the loop 7 will act as 85 a spring to clamp the loop 7 upon the pen-holder and thus to hold it firmly in position by means of the laterally extending arm 8. When in use, the foot or coil 9 rests 90 upon the surface of the paper which is being written upon; the angle of the pen-holder or pen to the paper may be adjusted by sliding the loop 7 along said pen-holder or pencil as the case may be, thus rendering 95 the device adjustable for different hands and for different methods of writing.

I claim:

1. A pen-holder support comprising a piece of wire with a loop intermediate its 105 ends adapted to encircle a pen-holder, said support terminating at one end in a laterally extending arm adapted to engage the upper side of said pen-holder and terminating at the opposite end in a foot adapted 110 when said pen-holder is in writing position to rest upon the surface being written upon.

2. A pen-holder support comprising a piece of wire with a loop intermediate its ends adapted to encircle a pen-holder and slidably thereon, said support terminating at one end in a laterally extending arm adapted to engage the upper side of said pen-holder and terminating at the opposite end in a foot adapted when said pen-holder is in writing position to rest upon the surface being written upon.
3. A pen-holder support comprising a piece of wire with a loop intermediate its ends adapted to encircle a pen-holder, said support terminating at one end in a laterally extending arm adapted to engage the upper side of said pen-holder and terminating at the opposite end in a coil constituting a foot adapted when said pen-holder is in writing position to rest upon the surface being written upon.
4. A pen-holder support comprising a piece of wire with a loop intermediate its ends adapted to encircle a pen-holder, said support terminating at one end in a laterally extending arm adapted to engage the

upper side of said pen-holder and terminating at the opposite end in a coil constituting a foot adapted to receive one finger of a hand when said pen-holder is in writing position to rest upon the surface being written upon.

5. A pen-holder support comprising a piece of wire with a loop intermediate its ends adapted to encircle a pen-holder, said support terminating at one end in a laterally extending arm adapted to engage the upper side of said pen-holder and terminating at the opposite end in a coil constituting a foot adapted when said pen-holder is in writing position to rest upon the surface being written upon, said loop and coil being located at one side of the portion of said support which joins them together.

In testimony whereof I have hereunto set my hand in presence of two subscribing witnesses.

RICHARD KELSEY.
